UNITED STATES PATENT OFFICE.

MIECZYSLAW MACKOWSKI, OF MILWAUKEE, WISCONSIN.

CURTAIN-STRETCHER.

1,284,395.

Specification of Letters Patent. Patented Nov. 12, 1918.

Application filed July 10, 1918. Serial No. 244,241.

To all whom it may concern:

Be it known that I, MIECZYSLAW MACKOWSKI, a citizen of Poland, residing at Milwaukee, county of Milwaukee, and State of Wisconsin, have invented certain new and useful Improvements in Curtain-Stretchers, of which the following is a specification.

This invention relates to improvements in curtain stretchers, and particularly to types 10 adapted to have disposed upon them curtains, drapery and the like, during the time of drying after being washed.

Another object is to provide means whereby a plurality of curtains may be attached upon the curtain frame at one and the same time, and

A still further object is to provide means whereby the engaging frame elements may be so folded, when not in use, as to present 20 a smooth surface, preventing the tearing and entanglement of clothing and the like when passing.

These and other like objects are attained by the novel construction and combination 25 of parts hereinafter described and shown in the accompanying drawings, forming a material part of this disclosure, and in which:—

Figure 1 is a plan view, showing a complete curtain stretcher made in accordance 30 with the invention.

Fig. 2 is an end view of the same, parts being broken away in order to disclose the construction.

Fig. 3 is another end view looking from 35 the opposite end of the apparatus.

Fig. 4 is an enlarged transverse sectional view, taken on line 4—4 of Fig. 1.

Fig. 5 is a similar transverse sectional 40 view showing the parts in another position.

Fig. 6 is a transverse sectional view showing a modified form of construction.

Fig. 7 is an enlarged front elevational 45 view showing the frame when in a folded or compact position.

Fig. 8 is a fragmentary view of the same looking from the other side.

Fig. 9 is a transverse sectional view, taken 50 on line 9—9 of Fig. 7, and

Fig. 10 is a similar transverse sectional view, taken on line 10—10 of Fig. 7.

The invention comprises two horizontally disposed bars 10 and 12, preferably made of wood in order to obtain a desired lightness

and a certain degree of resilience, the bars 55 being of such length as to equal that of longest curtains likely to be encountered.

The end, or transverse bars 14 and 15, are engaged so as to form a rectangular open frame, supporting the marginal edges of the 60 curtain so that air may pass through drying the same when in a taut or stretched condition.

Formed in the face or inner sides of the frame elements 10 and 12 are recesses 16, 65 enlarged at their bottoms 17, and extending longitudinally through all of the several bars which are also longitudinally recessed at 18 and also at their corners 20.

Hingedly engaged upon the surface 70 formed at the bottom of the recess 18, by hinges 21, are rails 22 in which are rigidly set a plurality of extending spurs 23, upon which the margins of the curtain are engaged.

The transverse elements 14 contain openings 24, adapted to receive the engaging pins 25 which pass through corresponding openings 26, formed at the outer ends of the longitudinal elements 10 and 12, whereby 80 the structure is held rigidly together, as can best be seen in Figs. 1 and 2.

In order to further hold the transverse bars engaged with the longitudinal bars, hooks 27 are pivoted upon screws 28 set in 85 the transverse bars, the hooks engaging with eyes 29 set in the longitudinal bars.

Engageable within the slots 16 and 17 are T-shaped heads 30 engaged with arms 31 extending inwardly, and pivoted with links 90 32, connected with the transverse elements 14 at both ends thereof, while in addition, to the transverse bars 15, are attached hooks 34 engaged with pins 35, set in the sliding elements 30 so as to hold the same rigidly. 95

Upon the base portions of the longitudinal bars 10 and 12 are fixed pins 38, to which are pivoted links 39 engaged with bolts 40 having heads 30' to which they may be clamped by the extending nuts 41, forming 100 a rigid, firmly secured structure when in an open position.

When it is desired to collapse the same, the transverse or cross elements are folded closely between the longitudinal bars 10 and 12, forming a compact structure, shown best 105 in Figs. 7 to 10 inclusive.

In the view shown in Fig. 6, in addition

to the element enumerated, all of the bars have longitudinally extending tenons 45 engageable in recesses 46, while in the recesses 16 and 17 are engaged T shaped heads 48, formed with bars 49, having extending ends 50, their inner ends 51 being flanged outward and screw-threaded to receive the clamp bolt 52, having a head 53; thus two or more of the frames may be rigidly secured together 10 when in an extended position.

From the foregoing it will be seen that all of the several parts may be so extended so as to form a compact frame, the length of which is readily adjustable and which may 15 be compactly folded.

Having thus described my invention what I claim as new and desire to secure by Letters Patent, is—

1. In a curtain stretcher, the combination 20 with a frame comprised of longitudinal and transverse bars capable of being folded side by side, of rails hingedly engaged in recesses formed in the inner sides of said transverse and longitudinal bars, a plurality of rigid 25 spurs fixed in said rails, and recesses formed

in said bars receptive of said spurs when said rails are in a forward position.

2. In a curtain stretcher, the combination with a frame comprised of longitudinal and transverse bars having recesses formed in 30 their base elements, one of said transverse bars having openings at the end thereof, pins adapted to pass through said longitudinal bars into said openings, hooks engaged upon the faces of said transverse bars engageable 35 with eyes secured in said longitudinal bars, sliding blocks engaged with said recesses, arms pivoted to said sliding blocks, means for clamping said hooks in an adjusted position therein, rails hingedly engaged in recesses formed in all of said bars, a plurality of rigid spurs affixed to said rails, upon 40 which the curtain is adapted to be suspended and means formed in said bars receptive of said spurs when said rails are folded there- 45 over.

In testimony whereof I have affixed my signature.

MIECZYSLAW MACKOWSKI.
